(57) **CLAIM**

The ornamental design for a syringe backstop, as shown and described.

DESCRIPTION

FIG. 1 is a front elevation view of a syringe backstop, showing our new design;

FIG. 2 is a rear elevation view thereof;

FIG. 3 is a right side elevation view thereof;

FIG. 4 is a left side elevation view thereof;

FIG. 5 is a top plan view thereof;

FIG. 6 is a bottom plan view thereof;

FIG. 7 is a top, front, right perspective view thereof;

FIG. 8 is a bottom, front, right perspective view thereof; and, FIG. 9 is a bottom, front, right view shown in condition of use for clarity of disclosure.

In the drawings, the equal-length broken lines depict environmental structure of the syringe backstop and form no part of the claimed design. In FIG. 9, the broken lines showing a syringe depict environmental structure and form no part of the claimed design. All broken lines form no part of the claimed design.
